UNITED STATES PATENT OFFICE.

CHARLES STRAUSS, OF PARIS, FRANCE.

FOLDABLE COMB.

Application filed October 15, 1926, Serial No. 141,773, and in France November 10, 1925.

This invention relates to improvements in foldable combs, and has for its main object the provision of an improved comb of this nature, that may be opened or unfolded and rigidly maintained in the unfolded or operative position by means of a slide provided for this purpose.

Another object of my invention is to provide a comb of this nature with an inset or non-projecting hinge that will be shielded or covered up when the comb is unfolded and ready for use, providing a perfect flat-sided comb and preventing hair from becoming caught on the said hinge.

15 A further object of this invention is to provide a comb of this nature with a hinge substantial and inexpensive in construction.

A still further object of the invention is to provide a comb of this nature with a slide of such a depth and construction that it will insure rigidity to the comb when in open operative position.

Other objects and novel features of construction of my improved foldable comb will 25 become apparent as the description proceeds.

Referring to the drawings forming a part of this specification:

Figure 1 is a front elevation of the comb with the slide moved back so that the comb 20 may be folded.

Figure 2 is a top plan view, partly in section, showing the comb partly opened.

Figure 3 is a top plan view of the comb in folded position.

35 Figure 4 is a front view of the same in elevation, and

Figure 5 is a section taken on line 5—5, Fig. 1.

Referring now to the drawings in detail, in which like numerals refer to the same parts throughout the several views, 10 indicates a comb comprising a section 11 hingedly connected to a second section 12 by means of a link 13 inserted into cutouts 40 or openings 14 and 15 in the innerly disposed ends of the comb sections 11 and 12. These sections 11 and 12 are provided with rounded edges 16 and 17, the object of which will shortly be described. The comb sections 11 and 12 are further provided with 45 grooves 18 and 19 extending along both their front and rear surfaces and near and parallel to their top edges. A comb opening member or slide 20 is slidably mounted on 50 the comb section 11 when the comb is in closed position. The comb may be folded

or closed with the section 12 in contact with either the front or rear surface of section 11.

When it is desired to open or unfold the comb from its closed or folded position as shown in Figs. 3 and 4, the slide or comb opening member 20 is slid along the grooves 18 in the section 11 and the forward end 21 will push against the link 13 and cause same to swing on its pivot pin 22 in the direction of the arrow Fig. 3 and partially open the comb, when the said end 21 will engage the rounded edge 17 and ride over same and the comb will be fully extended. A lug 23 on the section 12 acts as 60 a stop for the slide 20. It will be understood that in the event that the section 12 is folded in the opposite direction to that shown in Fig. 3 then the action will be 65 the same as above, but the section 12 will 70 swing in the opposite direction.

Section 12 is hingedly connected to the link 13 by means of a pin 24 passing through the comb and link. The pivot pins 22 and 24 allow for a relative movement of the sections 11 and 12 and the link 13 when the comb is being opened. The slide 20 is provided with an extension 25 on each side thereof to 75 cover the hinge portion of the comb when it is opened to operative position and thus prevent any hair from being caught between the link and the comb sections, as is the case in the foldable combs now in use that are provided with extending or projecting hinges. It will be seen that the slide 20 is 80 U-shaped in cross section, and that the extensions 25 thereon will act as a shield to 85 cover the hinge 13 on both sides thereof when the comb is in unfolded open position.

90 From the foregoing it will be seen that I have provided a foldable comb that is operable in either direction for opening and closing and having an internal or inset hinge adapted to be covered when the comb is unfolded, the comb being also provided with a slide adapted to act as a comb opener, thus avoiding the necessity of first alining the comb sections when it is desired to open same, and furthermore, the slide member, due to its length and depth will rigidly hold the comb sections against play or wabbling when in open or operative position.

Having described my invention, what I 110 claim as new is:

1. A foldable comb comprising a plural- 105 ity of sections, a cutout in each of the abut-

- ting ends of the sections, a hinge within the said cutouts, a groove on both sides of each of the sections, a slide operably mounted in the grooves of one of the sections adapted to unfold the comb when moved forwardly beyond the end of the said section, and a stop on the other sections to limit the movement of the slide.
2. A foldable comb, comprising a plurality of sections, an inset hinge intermediate the sections, a member slidably mounted on one of the sections adapted to unfold the

comb and maintain the sections rigidly in open, flat position and a portion on the slide adapted to cover the hinge when the slide is fully extended.

3. A comb comprising a plurality of sections hingedly connected, and a slidable shield mounted on the top edge of the comb adapted, when the comb is in open or unfolded position, to cover the hinge on both sides thereof, as and for the purpose described.

CHARLES STRAUSS.
